CONTROL PANEL FOR AIR-OPERATED INSTRUMENTS

Walter P. Wills, Philadelphia, Pa., assignor, by
mesne assignments, to Minneapolis-Honeywell
Regulator Company, Minneapolis, Minn., a cor-
poration of Delaware

Application May 31, 1947, Serial No. 139,385

Term of patent 14 years

(Cl. D52—1)

To all whom it may concern:

Be it known that I, Walter P. Wills, a citizen of the United States and resident of Philadelphia, in the county of Philadelphia and State of Pennsylvania, have invented a new, original, and ornamental Design for a Control Panel for Air-Operated Instruments, of which the following is a specification, reference being had to the accompanying drawing, forming part thereof.

Fig. 1 is a perspective view of the front of a control panel for air-operated instruments, showing my new design; and

Fig. 2 is a top view of the control panel for air-operated instruments.

The broken line illustration is for illustrative purposes only.

I claim:

The ornamental design for a control panel for air-operated instruments, substantially as shown and described.
